J. A. Wedder, of Troy, N. Y.
Letters Patent No 1201, dated Feb. 14. 1860.

The schedule referred to in these Letters Patent and marking part of the same.

To all whom it may concern:

Be it known that J. A. Wedder, of the City of Troy, in the County of Rensselaer, and State of New York, have invented or produced a new and Original Design for a Parlor Cook Stove; and I do hereby declare that the following is a full, and exact description of the same, reference being had by letters to the annexed photographic drawing which makes a part of this Specification.

Arrange the doors, &c. along the top of the upper front plate, &. and dispose the two ornaments, c. c. and the ornamental border, d. on the doors or panels, A, of the upper section of the stove; and arrange the ornaments, f. on the doors or panels, B, of the lower section of the stove; and place the stove-pork pillars, h, at the sides, and the rossette, i, over the middle, of the arched doorway or funnel of the lower front plate, J. - as represented in the annexed photographic drawing. -

What I claim as my invention or production & desire to secure by Letters Patent, is the ornamental design of the stove-plates herein described and
